UNITED STATES PATENT OFFICE.

JOHN W. HYATT, OF NEWARK, NEW JERSEY.

FILTER OF POROUS FABRIC.

SPECIFICATION forming part of Letters Patent No. 425,431, dated April 15, 1890.

Application filed May 22, 1889. Serial No. 311,693. (No model.)

To all whom it may concern:

Be it known that I, JOHN W. HYATT, a citizen of the United States, residing at Newark, Essex county, New Jersey, have invented certain new and useful Improvements in Filters of Porous Fabric, fully described and represented in the following specification and the accompanying drawings, forming a part of the same.

10 The object of this invention is to secure a very compact and efficient filter by folding or piling layers of fibrous fabric together with fine interspaces in such a manner as to provide a very large filtering surface or area

15 within a small space.

The invention consists, substantially, in folding or piling the layers of suitable fibrous fabric, as cloth or paper, upon one another, with fine intervening spaces, and such interspaces being obstructed alternately at the opposite edges of the fabric to prevent the direct passage of the fluid through such interspaces, and to furnish an outlet for the fluid after penetrating the thickness of a single layer. The fluid to be filtered is then applied to one edge of the layers of fabric and escapes by entering the alternate interspaces at such edge, passing through the intervening layers of fabric to the adjacent interspaces and escaping therefrom at the opposite edges of the fabric. By presenting the edges of the fabric to the unfiltered fluid a large number of layers may be inserted in a very small water-way, while the obstruction of the alternate interspaces, as described herein, permits the rapid percolation of the water through the filtering material, as it is compelled to pass through only a single layer to reach an outlet.

40 Paper has long been used to form the most perfect chemical filter, and I therefore prefer to use wood-pulp paper in thick sheets as the filtering medium for my construction. Such material is not adapted to sustain the pressure of the unfiltered fluid over a large area, and I therefore sustain it by providing numerous small ribs between the several layers transverse to the edges of the interspaces to support the material at frequent intervals.

50 The invention is shown in several forms herein, and will be fully understood by reference to the annexed drawings, in which—

Figure 1 shows a long narrow strip of such paper grooved transversely part of the way across. Fig. 2 is an edge view of the same 55 where the grooves are exposed. Fig. 3 represents a transverse section of two such strips laid upon one another with the open ends of their respective grooves or channels at opposite edges of the pile. Fig. 4 represents in 60 end view a coil formed of two such layers wound spirally upon a wooden core. Fig. 5 represents in section a glass tube with one end plugged by such a filtering-coil. Fig. 6 represents in longitudinal section a pile of 65 plain paper sheets separated at their alternate opposite edges by narrow obstructing-strips, and the interspaces filled with wire cloth or netting. Fig. 7 shows a pair of paper strips S, with tongues S' upon opposite 70 edges; Fig. 8, a plain sheet T, adapted to interpose between the same. Fig. 9 represents the end of a spiral coil, formed by winding the sheets S and T together upon a wooden core. Fig. 10 is a longitudinal section of the 75 coil shown in Fig. 9. Fig. 11 is an external view of a filter-casing adapted to contain such filtering material. Fig. 12 represents the same in longitudinal section, adapted to retain a coil or pile of any of the constructions shown, clamped at its opposite edges between the tapering seats and sustained upon perforated screens. The screens o are shown in section; but the filtering material N is not sectioned, as its construction is fully shown 85 in Figs. 6 and 10. Fig. 13 is a detached view of one of the screens adapted to fit a circular casing.

In Figs. 1, 2, 3, and 4, a represents a strip of paper of suitable length and width; b, 90 grooves formed transversely in the same, either by molding the strip or sheet from paper-pulp or by operating upon a flat sheet with a circular saw. Such grooves are formed nearly all the way across the paper, leaving a 95 longitudinal seat b² along one edge of the strip, and transverse ribs b' extending from the seat to the opposite edge of the strip. By laying two such transversely-grooved sheets upon one another, with the ends of the grooves at the opposite edges, as shown in Fig. 3, and winding the two strips together spirally upon a wooden core n, as shown in Fig. 4, it is obvious that the ends of the grooves in the al-

ternate strips are exposed at one edge or end of the coil, while the ends of the grooves in the intervening strips are exposed at the opposite end or edge of the coil, as shown in Fig. 5, where the coil is represented operating as a filter-plug in the bottom of a test-tube T. The liquid within the tube has access to the grooves in the alternate strips, (see arrows c,) and then escapes from the same only by percolating laterally through the remaining substance of the strip into the grooves of the intermediate strips, from the lower end of which it has free outlet. (See arrows d, Fig. 5.)

15 As all the grooves which open upwardly are obstructed at their lower ends, and as the ribs between the several grooves hold the structure rigidly in shape, it is obvious that the sheets may be made of any desirable dimensions and the coil be extended to any magnitude desired. The real area of the filtering-surface is obviously in such construction the internal areas of the grooves, from which the material escapes through the substance of each layer to its final outlet, and the entire filtering-area, with a mass of given diameter, may thus be made many times greater than the mere cross-section or area of such diameter, which is the area when a single 30 layer of filter-paper is employed for filtering within a funnel. The spirally-constructed plug shown in the bottom of the glass tube in Fig. 5 thus possesses a much greater filtering capacity than a larger structure in which the filter-paper is exposed transversely to the current of the fluid.

Instead of grooving the paper narrow strips of paper may be interposed alternately between the opposite edges of wider strips 40 piled or wound together, as indicated by the section in Fig. 6, in which case the fluid, when applied to the edges of the strips, would have access to the alternate interspaces between the wide strips, and could only escape from the same by percolating through the substance of the wide strips to the intermediate spaces, which have their outlets at the opposite edge. In Fig. 6 such wide strips are shown at e. The narrow strips which form 45 the seats at the edges of the strips at e' and the interspaces are shown kept open by filling them with wire-cloth w, adapted to furnish in its transverse wires the ribs required to support the paper and to perform the same function as the ridges or ribs b' in Fig. 55 1—namely, to hold the paper separated at frequent intervals in lines transverse to the seat b², so that the liquid entering the edges of the interspaces may penetrate across the strip to the seat at the opposite side to percolate laterally through the filtering material. The longitudinal wires of the wire-cloth being bent repeatedly back and forth over the transverse wires, permit the fluid to pass by them in its transverse movement across the strip.

Instead of grooving the strips, as in Fig. 1,

or using wire-cloth to hold the interspaces open, the ribs may be provided by forming the seats from paper similar to the filtering material with lateral interspaces l, as shown at S S' in Fig. 7, such seats and tongues being piled or wound together with plain intervening sheets T', Fig. 8, the spiral construction being clearly shown in Figs. 9 and 10. In the latter figure the section is taken through the interspaces l, Fig. 7, which may be left open or filled with sand l', if required, to prevent the obstruction of the channels by the swelling of the porous fabric, and to secure the free percolation of the water through such channels to their outlet.

Fig. 12 shows a casing I, with inlet g and outlet h, and divided transversely at the middle, where it is provided with flanges J, which 85 may be secured together by bolts k, or other suitable means. The casing is provided adjacent to the inlet and outlet with tapering seats m, adapted to fit the ends of the filter material N, and perforated screens o, formed 90 of flat sheet metal, are shown applied within the casing at each end of the filter material to sustain the same under any fluid-pressure to which it may be exposed. The screen would be so constructed by forming the perforations of sufficient number and fineness, or by grooving its surface, so as to distribute the fluid freely to the exposed ends of the water-channels between the alternate layers of filtering fabric, and the fluid entering 100 through the inlet g would thus pass rapidly from the material N and escape at the outlet h; the fluid entering any particular water-channel being compelled to pass only through a single layer of filtering material to reach 105 an outlet, as clearly shown by the arrows in Figs. 3 and 5.

It will be understood that where the construction is formed in a spiral coil the successive coils may be cemented together, or 110 the outer ends only of the layers forming the coil may be secured in any convenient manner to the periphery of the coil, as by a separate piece of wrapping or envelope fabric q, secured with waterproof cement, as at Fig. 115 9, or otherwise.

It will be noticed that with the construction shown in Figs. 1 and 7, where the interspaces consist in separate water-channels extending transversely part of the way across the layers, 120 there is no opportunity for the fluid which enters one edge of the boiler or coil to escape laterally, but that the fluid can only escape by such water-channel by percolation through the adjacent substance into the adjoining 125 outlet-channels. Where the interspaces between the layers are continuous, and the interspaces filled with open or loose material, as is presumed where wide and narrow strips are laid alternately upon one another, as 130 shown in Fig. 6, the extreme ends of such continuous interspaces would be closed in any convenient manner to confine the fluid to percolate through the intervening wide

strip. When such wide and narrow strips are wound in a spiral coil, as indicated in Fig. 9, the inner end of the continuous water-channel is readily closed by suitable cement, and the outer ends at the periphery of the coil are readily closed by the means used to secure the ends of the layers, as the separate piece *q*. (Shown in Fig. 9.) Such piece would, if the filter were intended for water, be cemented over the ends of the interspaces to close them at such point with waterproof cement, or with glue, if the filter be intended for alcohol, gasoline, or similar fluids.

Sand or other granular material of loose or open texture—as charcoal, which produces a very beneficial effect in purifying and sweetening water—may be readily applied to the wide strips *e* in the process of winding them into a spiral with the narrow strips *e'* by applying the sand with any suitable feeding mechanism to the surface of the wide strips as they are rolled into the spiral form, or by cementing the sand upon a suitable portion of the wide strips before rolling it together. The tapering seats *m* (shown in the heads of the casing in Fig. 12) may be replaced by flat seats upon the heads if the cylinder of filtering material *n* is made to fit the casing snugly and the seats are fitted directly to the opposite ends of the filtering material so as to prevent the passage of the fluid outside of its periphery.

The softness of the fibrous material used in forming the filter operates readily to form a close joint upon the metallic surface without the use of any considerable pressure or the application of any intermediate packing.

It will be understood that the filtering material described is not intended for greatly protracted use if employed under conditions where the impurities deposited upon its surface would be liable to decomposition, but that the cheapness of the material and the ease with which it may be replaced in any filter construction render it available for use during a limited time, when it may be entirely discarded and an entirely new set of filtering-layers be substituted therefor.

Having thus set forth my invention, what I claim herein is—

1. In a filter, the combination, with a series of layers of fibrous material, of seats arranged

to form interspaces closed alternately at the opposite edges of the layers, and intervening ribs extending from the seats to the edges of the interspaces, as and for the purpose set forth.

2. In a filter, the combination of a series of layers of fibrous material arranged substantially as described, with interspaces closed alternately at the opposite edges of the fabric, and the interspaces filled with open or loose material to hold the interspaces open and the layers in the required position, substantially as set forth.

3. In a filter, the combination, with a series of layers of fibrous material coiled together, of intervening seats at their alternative edges to form interspaces closed alternately at the opposite edges of the layers, and intervening ribs extending from the seats transversely to the edges of the interspaces, as and for the purpose set forth.

4. In a filter, the combination, with a series of layers of fibrous material coiled together, of intervening seats at their alternate edges to form interspaces closed alternately at the opposite edges of the layers, ribs extending from the seats transversely to the edges of the interspaces, and a casing adapted to confine the unfiltered fluid to one edge of the layers, as and for the purpose set forth.

5. A filter consisting in a casing having an inlet and outlet, seats adjacent to such inlet and outlet, and a coil of layers of fibrous material wound together with interspaces closed alternately at the opposite edges of the layers and clamped between the seats, substantially as herein set forth.

6. A filter consisting in a casing having an inlet and outlet, seats adjacent to such inlet and outlet, and a coil of layers of fibrous material wound together with interspaces closed alternately at the opposite edges of the layers and clamped between the seats, with perforated screens at the ends of the coil within the casing, as and for the purpose set forth.

In testimony whereof I have hereunto set my hand in the presence of two subscribing witnesses.

JOHN W. HYATT.
